(57) **CLAIM**

The ornamental design for a tooth bar as shown and described.

DESCRIPTION

FIG. 1 is a perspective view of a tooth bar showing my new design.

FIG. 2 is a top plan view of the tooth bar of FIG. 1.

FIG. 3 is a bottom plan view of the tooth bar of FIG. 1.

FIG. 4 is a left side elevation view of the tooth bar of FIG.

1.

FIG. 5 is a right side elevation view of the tooth bar of FIG. 1.

FIG. 6 is a front end view of the tooth bar of FIG. 1.

FIG. 7 is a back end view of the tooth bar of FIG. 1.

FIG. 8 is a second perspective view of the tooth bar of FIG. 1, shown in a first environment of use; and,

FIG. 9 is a third perspective view of the tooth bar of FIG. 1, shown in a second environment of use.

The broken lines in the drawings are included for the purpose of illustrating unclaimed features and form no part of the claimed design.
